MASTER COPY SHEET

Edward Z. Lewis, Evanston, Ill., and William J. Menihan, Franklin, Pa., assignors to The General Manifold and Printing Company, a corporation of Pennsylvania

Application September 30, 1936, Serial No. 103,426

12 Claims. (Cl. 101—131)

This invention relates to a master copy sheet, and more particularly to a double duty copy sheet suitable for use in hectograph methods of reproduction. A master sheet is a piece of fairly hard paper or other suitable material, having a surface suitable for receiving an impression of characters typed or written in what is commonly known as hectograph ink.

To obtain the best results in reproduction from a master hectograph copy sheet, the kind of material, the weight and finish of the paper stock upon which the hectograph carbon is applied, as well as the paper stock upon which the copies are to be reproduced, are important factors. In the new method hereinafter presented the master hectograph carbon sheet and the record sheet may be made of selected paper stock to meet the requirements above set forth, and each sheet may comprise a long, continuous sheet of uniform quality, as well as shorter individual sheets. Furthermore, both sheets may consist of the same material.

The method ordinarily employed to make a master hectograph carbon copy is by inserting a sheet coated on one side with hectograph carbon material, (generally termed hectograph carbon paper) between two record sheets, and the impression is made by the typewriter or other means on the top sheet, thus producing a hectograph copy on the underlying sheet, which becomes the master copy sheet, and from which additional copies are reproduced by the gelatin pad method. In the making of a master hectograph carbon copy for use in reproduction of copies by a well known alternative method, i. e. on the rotary style of duplicating machine (where the master copy is attached to a cylinder) it is necessary that the writing of the master carbon copy be reversed, which is accomplished by placing the record sheet (the sheet on which the master copy is to be made) in front of the hectograph carbon sheet with the carbonized surface facing toward the record sheet. The impression is then made on the face of the record sheet and the hectograph carbon copy is thus produced on the back of said record sheet.

It will be seen that the sheet of hectograph carbon is necessarily handled in the various operations. The inherent nature of hectograph coating is such that it readily stains the hands and fingers when contacted.

The general object of the invention is to provide a master sheet which can be used effectively either in making copies or reproductions on the spirit type of reproducer or in producing copies on the gelatin type of reproducer, with little or no risk of soiling the fingers.

Another object of the invention is to provide a double sheet for hectograph use, so coated with transfer material that a master copy may be

made for use with either type of duplicator simply by typing on one side or the other of said double sheet.

An additional object is to provide a duplex sheet which may be conveniently placed in a typewriter or other machine without exposure of the coated surface.

A further object is to provide such a duplex copy sheet with a protective sheet which will prevent marking or smudging of the surface of the sheet on which the impression is to be made, prior to the typing operation, which will save the coating from injury, and which may be easily removed when the impression is to be received.

Another object is to provide a device of this character as a new article of manufacture in which both kinds of master copies may be made at one impression.

Another object is to provide an article of manufacture of this character in which substantially half of the coated area is folded to contact with the other half, to prevent smearing of the transfer material.

An additional object is to provide means for preventing the cracking or disintegration of the hectograph coating by folding back and forth continuous strips of hectograph coated paper in a pack, with an equal length of a continuous strip of blank master copy paper of the same width folded back and forth in similar folds with the ends of each strip projecting, whereby they may be pulled from the middle of the pack as a duplex sheet and inserted in a typewriter with either side facing the type, to provide conventional typing or reverse typing.

A further object is to provide a roll of superimposed sheets one of which is coated on one side with transfer material in contact with the other sheet, whereby the two sheets may be pulled from the roll as a single sheet and fed to a typewriter, either side up, to produce conventional or reverse typing on the sheet which is used as the master form.

Other objects and advantages will appear from a consideration of the following description.

Several embodiments of the invention are shown in the accompanying drawings in which:

Fig. 1 is a plan view of the duplex sheet with corners turned back to show the hectograph transfer coating and the wax tissue sheet;

Fig. 2 is an end view of the sheets moved apart to clarify the disclosure;

Fig. 3 shows the duplex sheet after the protecting sheet of wax tissue paper has been pulled out and after certain characters have been typed thereon;

Fig. 4 shows the duplex sheet with the typing on the opposite side;

Fig. 5 shows the inner surface of the upper half of the detached typed sheet of Fig. 4;

- Fig. 6 is a perspective view of the detached wax tissue sheet;
- Fig. 7 is an end view of a hectograph of the gelatin type;
- 5 Fig. 8 is an elevation of a spirit type duplicator;
- Figs. 9, 10 and 11 are perspective views of a modification;
- Figs. 12 and 13 are perspective views of another modification;
- 10 Fig. 14 is an end view of a further modification;
- Fig. 15 is a perspective view of an additional modification;
- 15 Fig. 16 is a perspective view of a further modification; and
- Figs. 17 and 18 are perspective views of the paper being folded into position for use.
- The duplex copy sheet comprises what may be called the upper sheet 10 and the lower sheet 11.
- 20 The under sides of these sheets are marked, for convenience, 10^a and 11^a. In the first form shown, they are preferably of the same size, and are connected at one or more points to hold them in registration but in such a way as to permit ready separation. They may, for example, be joined at the top edge, as shown in Fig. 1, wherein the two sheets comprise a single sheet folded at the middle and provided with perforations 12 to permit the two panels to be torn apart. The under side 10^a of the top sheet has a coating thereon of transfer material of suitable composition for use in hectograph machines either of gelatin type or spirit type reproducers. Such coatings are made of what is commonly known as hectograph ink.
- 25 This coating may cover the entire under surface or inner surface of the sheet, but preferably terminates short of the top and bottom, as better shown in Fig. 4.
- Between the two sheets or panels there is provided preferably a sheet of protective material, as for example oil or wax tissue paper 13, to prevent the coating from being transferred to the under sheet before the impression is to be made. In other words it prevents marking or smudging 40 of the lower sheet. This interleaved sheet may be held between the upper and lower sheets by gumming the same at one edge, as for example the top or bottom, by wire stitching or in other ways, whereby it may be readily removed before the typing is done. One method of holding said sheet is shown in Fig. 1 in which the three sheets are stapled together at 14 and a curved line of perforations 15 is provided in the top and bottom sheets, but not in the wax sheet. The latter, however, may have a cut-out or notch in the upper margin, as shown in Fig. 6. With this arrangement the sheets may be held by one hand at the upper margin, and the tab outlined by the perforations may be seized between the thumb and 45 finger of the other hand and torn out, thus removing the wax sheet, which is shown detached in Fig. 6. The staple holds the three sheets together at one side preventing them from blowing open and being accidentally folded-over and creased. Separation at the opposite side is prevented by the fact that the inner sheet is enclosed by the two sections of the folded-over cover sheet. Insofar as the removal of the protective wax sheet is concerned, the same will be 50 prevented from falling out from between the folded-over sheet, if the former is secured to either of the two folded-over sections. In other words, said protective sheet may be stapled either to the upper or to the lower of the two panels 10 or 11, 55 which are provided with the line of perforations
- shown in Fig. 1, and detached by pulling out the tab. While the protective sheet may be secured to either the upper or lower sheets 10 and 11, it will be noted that if it is secured to the sheet having the transfer material on the back, i. e. 5 sheet 10, the only tab torn out will be torn out from sheet 10, which sheet is subsequently discarded in any case, leaving the typed sheet or master form 11 intact.
- As shown in Figs. 1 and 4, the duplex copy sheet 10 has indicia thereon to insure that the typing or writing thereon will be applied to the proper sheet. In Fig. 1, the sheet 10 has printing thereon, for example, instructing the operator to type on that sheet in order that the resulting master 15 sheet may be used for hectograph work, i. e. reproduction work in which there are two impressions made to produce the desired final sheet. The opposite or under side 11^a may have printed thereon instructions to type or write on that side 20 in order that the master sheet may be used for the spirit type of reproduction in which only a single impression is required to produce the final sheet.
- If the duplex copy sheet is to be used for hectograph reproduction work, the folded sheet is now inserted in the typewriter and typed on the upper face 10, as viewed in Fig. 3, and the letters or characters will be transferred to the lower sheet 11 with the said letters or characters in the 25 normal order, reading from left to right, as will be evident. In Fig. 3, part of the upper sheet is broken away to show the lower sheet. The top sheet 10 may now be detached and discarded, and the remaining sheet or panel, i. e. the so-called bottom sheet 11 used as an ordinary hectograph master copy sheet.
- Fig. 7 indicates a simple hectograph outfit in the form of a pan containing a layer of gelatin 16. If the said master copy sheet 11 is pressed 40 face downwardly against the gelatin and then removed, numerous copies may be made on other sheets by pressing them against the surface of the gelatin, as is well understood.
- If the master copy sheet is to be used with the 45 spirit type of duplicator, the duplex copy sheet is turned over before being put into the typewriter so that the typing is done on the outer face 11^a of the bottom sheet instead of on the outer face of the top sheet. The result of this 50 operation is shown in Fig. 4 in which the impression appears both on the front and on the back of the sheet on which the typing is done. The impression made by the hectograph ink appears on the face 11, the letters or characters appearing, however, in reverse order, as indicated in Fig. 5. The impression made on the front or face 11^a serves no purpose in making reproductions but is useful in reading the typed matter to see if it is correct. After the two sheets are 55 separated, as in the previous case, the typed sheet is used in the usual manner by attaching it to the cylinder 17 of the spirit duplicator, shown in Fig. 8, the reverse typing, in hectograph ink, facing out. As the moistened sheets of paper 18 are rolled against the exposed sheet 11 of the master copy sheet, the writing is reversed as it is transferred thereto and appears with the letters in conventional order, as is well understood. It will be seen that whether the duplex form is 60 typed on the front or the back, the coated sheet 10 is discarded in either case and the coated surface 10^a need not be touched, particularly where there is an uncoated margin at one or both ends of the sheet.

It will be seen that one essential difference between the hectograph and the spirit machine is that in the former and after the typing operation is completed, there are two impressions made, i. e. the typed material is transferred first to the gelatin and then from the gelatin to the final sheet. In the spirit type machine, after the typing is finished there is only one impression made, which transfers the material from the master copy to the moistened final sheet.

The present improvement provides a unit form which comprises both a hectograph ink coated sheet and a master copy record sheet in which the copy is always produced on the record sheet and in which the sheet or sheets may be made of the material best suited for the purpose. Since the sheets are attached to each other in a manner to make them substantially an integral unit, it becomes unnecessary for the hands to come in contact with the hectograph coating at any time. The wax tissue sheet or other protective sheet prevents any offset of the hectograph coating against the face of the adjacent sheet. A further advantage of this, aside from the matter of cleanliness, is that a clear, sharp copy, suitable for reproduction, is made on the master copy.

In Figs. 9, 10 and 11, a slightly modified form of unit is illustrated. The sheet 19 is folded over near the middle to form two panels, one of which is shorter than the other. The shorter sheet is coated on the under side, the longer one having a projecting margin. On this margin may be printed instructions to the effect that by typing with this side up, a master sheet will be produced which may be used with the gelatin type equipment. On the back of the longer panel may be printed instructions with reference to typing on that side to produce a master copy for the spirit type machine. The protective sheet 20 is preferably longer than the shorter of the two panels and may be detachably fastened at its upper end to the folded sheet as by gumming or otherwise, whereby it may be pulled out. Said sheet may, for example, be stapled to the under sheet, similarly to the arrangement in Fig. 1, with perforations in said under sheet, or it may be secured in various other ways. After the short panel is torn off and discarded, the instructions remain printed on the longer panel as an aid in further handling of the same, although the characteristic appearance of the hectograph ink and the arrangement of the typing, forward or backward, makes it evident with which type of apparatus the master copy is to be used.

Fig. 12 shows a further modification in which a sheet of material 21 is folded back and forth in the form of a W, forming four panels, with a coating on half of one side of the sheet. In other words, the coating covers two panels whose inside surfaces face each other, thus preventing smudging. The ends 22 of the two outside panels are preferably longer than the intermediate fold whereby the two protruding ends may be held in the hand and a pencil or ruler 23 inserted in either of the two V shaped loops, as shown in Fig. 13, and the folded paper pulled out into a length of paper having a single fold therein, substantially half of the strip of paper being coated. With the sheet in this form it is ready for use in the manner previously described. It will be seen that the folded arrangement in Fig. 12 makes unnecessary the use of a protective sheet of oil paper or wax tissue.

Fig. 14 shows a further development of the same idea. A strip of paper or suitable mate-

rial 24 is coated on one side and is folded as a fan-fold, all the folded sections being coated on the inner surfaces which face each other and therefore cannot with ordinary handling come in contact with the fingers or with other objects. 5 A strip of record paper 25 is also folded in like manner. The carbon coated sheet is indicated by the heavier of the two lines. If the two projecting ends 26, which are in parallel relation and superimposed with the carbon coated sheet 10 in contact with the other sheet, are pulled outwardly and fed around a typewriter platen, it will be seen that a continuous master form is provided. Subsequent rotation of the platen continues to pull out the necessary lengths of the 15 duplex slip and without cracking or damaging the carbon coating. The two fan-folds may be stored in a suitable container and as the strips are pulled out they move at the same rate and do not slide one over the other in a manner to cause 20 smudging or smearing of the coating. It is understood, of course, that the composite strip may be fed into the typewriter with either the coated or the uncoated strip on top so that the typing may be reversed or otherwise, depending on the 25 type of master form desired.

In Fig. 15, two strips of paper 27 are rolled up on a suitable spindle 28. These two strips, as in the previous case, comprise respectively a coated strip and a record strip and the type of master 30 form produced is determined by mounting the roll either in the position shown or reversed end for end in suitable supports 29, which are shown somewhat diagrammatically in this figure. These supports are mounted on or to the rear of 35 a typewriter so that the strips may be fed into the machine continuously and cut off or torn off in shorter sheets of the required length.

Figs. 16, 17 and 18 show an arrangement which makes it possible to make both kinds of master 40 copies at one impression. The sheet 30 is folded into four panels 30¹, 30², 30³, 30⁴, two of which are coated on the inside with transfer material, as shown by the heavier line. These coated surfaces are folded against each other to prevent 45 smudging. If these two coated panels are partially opened, as shown in Fig. 17, and folded around the remaining two folded panels, as shown in Fig. 18, it will be seen that two of the four panels, i. e. 30³ and 30⁴, will constitute 50 master copy sheets with the typing on panel 30⁴ in regular order and on panel 30³ in the reverse order and both made by the same impressions of the type against the paper, i. e. against the outside surface of panel 30². In like manner if 55 the typed impression is made on panel 30¹, a copy will appear on panel 30³ in the conventional order and concurrently a copy will be made on panel 30⁴ in the reverse order. The two master copy panels may be detached from each other and from 60 the remaining two sheets, which are discarded.

By way of summary, the device provides a unitary double duty master copy which, when marketed, is designed to protect the hectograph coating, which coating when the sheets are arranged in a stack or in a box is tightly pressed against the wax sheet without rubbing and hence the coating itself will not deteriorate by exposure to air or light; the oil tissue paper does not absorb the copying ink or permit any disfigurement of 70 the master copy section before the same is ready for use; and merely by writing on one side or the other of the device either kind of master copy is produced. The necessary instructions may be printed near the top of each of the two outer 75

4 sheets so that the user will insert the sheets properly in the typewriter to make the type of master copy desired.

We claim:

- 5 1. A copy sheet for use either in the gelatin type or in the spirit type of reproduction, comprising upper and lower panels of sheet material the outer sides of which are adapted for writing thereon, the inner side of one of said panels being 10 coated with hectograph ink, a sheet of protective material between said panels, and means holding all of said sheets in detachable relation.
- 15 2. A copy sheet of the character set forth, comprising a piece of paper folded and weakened along a center line, thereby forming superimposed panels, the outer side of each panel having a surface adapted for typing thereon, and the inner side of one of said panels having a coating of hectograph transfer material thereon with un- 20 coated margins at the top and bottom, said panels having registering detachable portions at one of their edges, said portions being fastened together.
- 25 3. A copy sheet of the character set forth, comprising a piece of paper folded at its middle, forming upper and lower panels, the outer side of each panel having a surface adapted for writing thereon, the inner side of one of said panels having a hectograph transfer coating, said panels having registering detachable tabs at one edge, 30 and a sheet of protective material interposed between said panels and fastened to each of said detachable tabs.
- 35 4. A copy sheet of the character set forth comprising a strip of paper folded at its middle, forming upper and lower sections, the outer side of each section having a surface adapted for writing thereon, and the inner side of one of said sections having a coating of hectograph transfer material, said sections having registering detachable tabs formed by lines of perforations near the 40 edges of said sections, said tabs being fastened together, and a sheet of non-adhesive tissue interposed between said sections and removable therefrom with said tabs.
- 45 5. As a new article of manufacture, a sheet of material folded on three transverse lines to form four panels, half of said sheet being coated on the inner side with hectograph transfer material, whereby the two panels comprising said coated 50 half sheet may be folded face to face to prevent smearing of said material prior to using the same, and whereby said two coated panels may be folded over the other two folded panels to make two master copy panels, each having characters 55 thereon made from the same impression, but one set of characters being reversed in arrangement with respect to the other.
- 60 6. A copy sheet for use either in the gelatin type or in the spirit type of reproduction, comprising two sheets of material detachably secured to each other whereby one may be discarded, one side of each of said sheets being adapted for writing thereon, the opposite side only of one of said sheets being coated with hectograph ink, a sheet 65 of protective material between said two sheets and means detachably holding said sheet of protective material to one of said two sheets, to prevent smudging of the hectograph ink over the surface of the adjacent, uncoated sheet, prior to 70 writing on either of said two sheets.
- 75 7. A copy sheet of the character set forth, comprising a piece of paper folded and weakened along a center line, thereby forming superimposed panels, the outer side of each panel having a surface adapted for typing thereon, and the inner side of one of said panels having a coating of hectograph transfer material thereon with un- 80 coated margins at the top and bottom, one of said panels having a detachable portion at one of its edges, and a sheet between said superimposed panels, fastened to said detachable portion.
- 85 8. A copy sheet of the character set forth, comprising a piece of paper folded at its middle, forming upper and lower panels, the outer side of each panel having a surface adapted for writing thereon, the inner side of one of said panels having a hectograph transfer coating, one of said 90 panels having a detachable tab at one edge, and a sheet of protective material interposed between said panels and fastened to said tab.
- 95 9. A copy sheet for use either in the gelatin type or in the spirit type of reproduction, comprising two sheets of material detachably secured to each other whereby one may be discarded, one side of each of said sheets being adapted for writing thereon, the opposite side only of one of said sheets being coated with hectograph ink, a sheet 100 of protective material between said two sheets to prevent smudging of the hectograph ink over the surface of the adjacent, uncoated sheet, and means for detachably holding said sheet of protective material in place, whereby it may be removed prior to writing on either of said two sheets.
- 105 10. A device for making a master copy sheet for use either in the gelatin type or in the spirit type of reproduction, comprising two sheets of substantially the same size arranged in superimposed relation, a hectograph transfer ink coating on the inner face of one of said sheets, whereby a typed impression made on the opposite side of said 110 coated sheet will be transferred to the inner face of the other of the two sheets, with the letters in the conventional order from left to right, whereas a typed impression made on the outer face of said other sheet will appear on the inner face thereof, with the letters in the reverse order, and a sheet of protective material between said superimposed sheets in contact with said inner faces to prevent smudging of the uncoated inner face by the 115 coated face, prior to either of the aforesaid typing operations, said protective sheet being removable to permit said typing operations.
- 120 11. A copy sheet of the character set forth, comprising a piece of paper folded and weakened along a center line, thereby forming superimposed panels, the outer side of each panel having a surface adapted for typing thereon, and the inner side of one of said panels having a coating of hectograph transfer material thereon with un- 125 coated margins at the top and bottom, and a protective sheet positioned between said panels and of a size to cover the coated area, but leaving an uncovered area at the top margin, whereby said panels may be grasped near the fold at the top without smudging the surface which faces said top margin, and said protective sheet withdrawn by a downward pull.
- 130 12. A copy sheet as in the preceding claim in which the uncovered area is defined by a notch in the top margin of said protective sheet.
